Orlando V. Flora,

United States Patent Office.

ORLANDO V. FLORA, OF MADISON, ASSIGNOR TO HIMSELF, GEORGE SHAN-
NON, AND D. C. ROBINSON, OF JEFFERSON COUNTY, INDIANA.

Letters Patent No. 79,566, dated July 7, 1868.

IMPROVEMENT IN VISES.

The Schedule referred to in these Letters Patent and making part of the same.

TO ALL WHOM IT MAY CONCERN:

Be it known that I, ORLANDO V. FLORA, of Madison, in the county of Jefferson, and State of Indiana, have invented new and useful Improvements in Adjustable Vises; and I do hereby declare that the following is a full, clear, and exact description thereof, which will enable those skilled in the art to make and use the same, reference being had to the accompanying drawings, forming part of this specification.

This invention relates to that class of vises by which we are enabled to clamp any form of article, whether its sides be parallel or inclined.

Figure 1 is an elevation of the vise.

Figure 2 is a plan.

Figure 3 is a horizontal section through the line A B, fig. 1.

Similar letters of reference indicate corresponding parts.

A and B are, respectively, the fast and loose jaws of the vise.

C is a box or nut, which passes through the fast jaw, and in which turns the screw D. This screw passes loosely through the trunnion-washer E, which is supported vertically by means of the journals or trunnions *a a*, these journals having bearings in the loose jaw B. Where the screw D impinges on the washer there is a double bevel, as shown in fig. 1, for the purpose of giving the screw a good bearing when the vise is either closed or open. These vertical journals also allow a fair bearing for the head of the screw D, when a bevelled piece, *m*, is clamped in the vise, as in fig. 2.

F F are guides or supports, attached rigidly to the fast jaw, and projecting horizontally, as shown.

On the lower end of the loose jaw are the lugs or journals G G, which have bearings in the elliptical openings in the supports F F, and are kept up to the front side of the said openings by means of the notched gib or key *n*, when using the vise to clamp pieces parallel on both sides. But when clamping a bevelled piece, as *m*, in fig. 2, the key *n* is pushed back until the notches or wards engage with the pieces F F, thus allowing room for considerable diagonal play in the elliptical openings by the lugs or journals G G, and, in consequence, the upper part of the loose jaw accommodates itself to any bevel in the piece clamped, this being clearly shown in figs. 2 and 3 of the drawings.

The key *n* may be again put in place when desired by the operator.

Having thus described my invention, what I claim as new, and desire to secure by Letters Patent, is—

1. The combination of the jaw B, vibrating washer E, and screw D, all constructed and arranged substantially as described.

2. The jaw B, with lugs G on the lower end of its shank, in combination with the supports F and gib *n*, all constructed and arranged substantially as described.

ORLANDO V. FLORA.
